Frank J. Johnson
ATTORNEY

UNITED STATES PATENT OFFICE.

RALPH T. MORGAN, OF SAN FRANCISCO, CALIFORNIA.

AUTOMATIC RELEASE FOR SAFETY VALVES.

Application filed November 13, 1919. Serial No. 337,875.

To all whom it may concern:

Be it known that I, RALPH T. MORGAN, a citizen of the United States, and a resident of the city and county of San Francisco, State of California, have made a new and useful invention, to wit, Improvements in Automatic Releases for Safety Valves; and I do hereby declare the following to be a full, clear, concise, and exact description of the same.

This invention relates particularly to a mechanism for automatically closing a safety valve in the high pressure steam line connected to a steam turbine with an object of providing in the novel arrangement, construction and combination of parts, as will be hereinafter more specifically described, a simple and effective mechanism, that may be cheaply manufactured and easily installed. Other objects and advantages will appear as the description advances.

Steam turbines used for ship propulsion and in industrial and power house work develop an enormous velocity, varying from 300 to 29,000 revolutions per minute, which is requisite for high efficiency and necessitating that the machine be geared down to be of practical use. Because of its high efficiency the turbine has been extensively used as a marine engine and has proven to be a commercial success, but its desirability for driving ships' propellers has not been so great as for stationary work since the speed conditions promoting efficiency in propellers and land turbines are antagonistic. Turbines demand high rotative speeds, and propellers comparatively low ones. The result is that compromise designs of turbines for marine work have been made, it having been necessary to interpose a speed reducing medium between the turbine and propeller comprising either herring-bone or helical tooth gears or electrical generator-motor combinations.

In ordinary installations on merchant ships and war vessels the practice has been to use the helical-tooth gears exclusively for speed reduction and it is to this class of installations that my improvement is adapted. The reducing medium generally comprises a helical-tooth pinion directly connected on the turbine shaft and meshing with a helical tooth gear of a larger diameter adapted

to give the required slow rotative speed and which is connected with the propeller shaft.

The high efficiency of the turbine has been distributed to the propeller shaft by accurately cutting the meshing helical teeth on both pinion and gear to a calibrated fineness to insure smooth action and an even distribution of stresses. The process of cutting and milling these gears is necessarily a slow, tedious and expensive one and it is necessary to run the reduction gears in an oil bath within the gear casing to increase the efficient action thereof and to prevent overheating, crystallization and a stripping of gear teeth.

Where the gear teeth have become stripped it becomes necessary to replace new gears. New turbine reduction gears in this day of high cost of material and labor run into exceedingly large sums besides placing the ship or power unit out of commission as an active money maker. The improvement submitted herewith contemplates a mechanism and structure which will automatically stop the turbine reduction gears from operating should a defect occur in the oil supply system.

Ships or installations using turbines with a gear reduction require individual lubricating oil tanks for the storage of oil that is continuously pumped into and from the gear box, the oil within the gear box being whipped into a froth or foam by the excessive speed at which the gears revolve. It becomes very necessary that the operator in charge of operating the turbine watch his oil level in the storage or settling tank and disconnect the steam supply to the turbine when the oil level gets below a certain point, dangerous to the operation of the turbine.

The object of my improvement as illustrated in the drawing consists in providing mechanism whereby the steam supply to the turbine will be automatically shut off when the oil level within the storage tank has reached the danger point either by reason of the oil storage tank supply pump becoming inoperative or by a leak from the gear casing or supply pipes.

In this specification and the annexed drawings, the invention is disclosed in the form considered to be the best, but it is to be understood that the invention is not

limited to such form, because it may be embodied in other forms, and it is also to be understood that in and by the claims following the description it is desired to cover the invention in whatever form it may be embodied.

In the accompanying one-sheet of drawing:

Fig. 1 represents a vertical cross section thru a ship's hull with a diagrammatic application of my improvement applied to the engine room auxiliaries and turbine.

Fig. 2 is a vertical section taken thru an oil settling tank illustrating the immersed float mechanism.

Fig. 3 is an elevation of the lever for operating the butterfly valve on the main steam line together with the mechanism for releasing the same.

Referring to Fig. 1 the numeral 2 designates the storage or oil settling tanks which according to usual practice are located amidships in the hatch of the engine casing, and adjacent the upper decks, to permit a gravity flow of the oil to the point of distribution. I have shown two storage tanks for the lubricating oil, which is in accordance with engineering practice, to guard against the contingency of one tank becoming defective or to be used as a reserve tank when the oil in the used tank has become dirty or a residuum precipitated by the frothing action of the rotating gears.

The gear casing unit is diagrammatically represented by the numeral 3 and has the gravity oil supply line 4 connecting the same to the storage tank 2, which is filled thru the supply line 5 from the lubricating oil pump 6, having a suction feed line connected to the gear casing unit and which is adapted to draw oil from the gear casing. Within the storage tank 2 I provide the standard 7, rigidly welded, or secured to the bottom of that tank and having the rod 8, secured to the spherical hollow, metal float 9 completely immersed in the oil and substantially in the middle of the tank and fulcrumed on the pivot 10 therein. The projection 11 formed on the standard 7 is adapted to limit the vertical movement of the float 9 as the oil level rises. The other end of the rod 8 is pivotally connected to the forked rod 12 extending thru the guide bushing 14, secured in the top plate of the tank, and is slidably connected to the rod 15, having an end 16 thereof pivotally secured to a bracket 17 on the tank top. The end 18 of the rod 15 overhangs the tank 2 and has the wire 19 secured thereto extending to the lever 20 that rotates the butterfly valve enclosed within the casing. The butterfly valve 22 is installed in the main steam line 23 leading from the boilers, according to the United States Merchant Marine regulations, and is provided with

the hand lever 20 for manually operating the same. The quadrant 24 is mounted on the valve casing and provided with the notches 25 and 26 adapted to be engaged by the latch rod 27 slidably guided on the lever 20. The light compression spring 28 is secured to the latch rod 27 for holding the same in engagement with the quadrant notches 25 and 26. The end of the latch rod 27 has the button head 29 formed thereon as a finger grip for disengaging the latch from the notches.

The bracket 30 is rigidly mounted on the upper side of the butterfly valve and is provided with the guide bushing 31 on the end thereof thru which the end of the wire 19 is inserted. On the under side of the bracket 30 I provide the bell crank lever 32 having the elbow thereof pivotally connected to the bracket 30 and having the arm 33 thereof connected to the end of the wire 19. The other arm 34 is forked or bifurcated and is adapted to receive the handle of the lever 20 therebetween to permit the button head 29 on the end of the latch rod 27 to engage in frictional contact with the forked arm 34.

The device operates as follows: Under normal steaming conditions the lubricating oil pumps are continuously pumping oil from the gear casing to the storage tanks where it flows by gravity back to the reduction gears. The oil while in the storage tanks is not under pressure and is maintained at a level indicated by X' which is the normal safe supply level. If an accident occurs and the pumps fail to keep the oil at the normal level and the level drops to the danger point X'', the ball float fulcrumed on the standard 7, completely immersed in the oil at a predetermined point, drops with the oil surface forcing the forked rod 12 upward, causing it to lift the beam 15 which in turn pulls up the wire 19, and arm 33 of the bell crank 32, causing the arm 34 to swing radially against the button head 29 on the latch rod 27 and to disengage the latch 27 from notch 25. The tension spring 35 secured to the valve casing at 36 and to the lever 20 on the butterfly valve, pulls the lever 20 downward in the direction of arrow "a" so that latch 27 locks in the notch 26, thus closing the butterfly valve and thereby disconnecting the steam supply from the turbine. The projection 37 on the quadrant 24 limits the movement of the lever 20.

Modifications in structure will suggest themselves to those skilled in the art and I do not wish to limit myself to the structure shown and described but I believe the particular adaptation of the float 9 in a lubricating oil storage tank completely immersed in the liquid, at a point far below its highest level in combination with the mecha-

nism for automatically closing the safety butterfly valve is new subject matter and that which I claim and desire to secure by Letters Patent is:—

- 5 1. In combination with an engine, a throttling valve therefor, an operating lever for controlling the valve, a fixed quadrant adjacent the valve, a latch-rod carried by the lever for engaging the quadrant to hold the lever in a set position, a lubricating system for the engine including a lubricant gaging device, a lever operable by said device to disengage the latch-rod from the quadrant when the lubricant supply is low, and means 10 for moving the lever to inoperative position when the latch-rod is so disengaged.
- 15 2. In combination with an engine throttling valve and a lubricating system for the

engine, a lubricant gaging device, a bell-crank pivoted on the throttling valve casting and having one end connected to the device to be operated thereby and its opposite end bifurcated, a throttle lever for operating the valve and movable within the bifurcated end of said bell-crank lever, means 20 for holding the throttle lever in a set position and consisting of a latch rod carried by the latter and engaged by the bifurcated end to release the throttle lever when the lubricant supply is low, and means for moving the throttle lever to inoperative position when released.

In testimony whereof, I have hereunto set my hand at San Francisco, California, this 7th day of November 1919.

RALPH T. MORGAN.
